[57] CLAIM

The ornamental design for a front face of a vehicle wheel, as shown and described.

DESCRIPTION

FIG. 1 is a front view of a front face of a vehicle wheel according to my novel design; and,

FIG. 2 is a perspective view of the front face of a vehicle wheel according to my novel design.

Features shown in dash lines depict the environment and do not form part of the claimed design.

1 Claim, 1 Drawing Sheet

FIG. 2

FIG. 1
